(57) **CLAIM**

The ornamental design for a yard light, as shown and described.

DESCRIPTION

FIG. 1 is an overall perspective view of a yard light showing a first embodiment of my design;

FIG. 2 is a front elevational view of the yard light of FIG. 1;

FIG. 3 is a rear elevational view of the yard light of FIG. 1;

FIG. 4 is a right side elevational view of the yard light of FIG. 1, the left side being a mirror image;

FIG. 5 is a top plan view of the yard light of FIG. 1; and

FIG. 6 is a bottom plan view of the yard light of FIG. 1.

FIG. 7 is an overall perspective view of a second embodiment of a yard light showing my design;

FIG. 8 is a front elevational view of the yard light embodiment of FIG. 7;

FIG. 9 is a rear elevational view of the yard light embodiment of FIG. 7;

FIG. 10 is a top plan view of the yard light embodiment of FIG. 7;

FIG. 11 is a bottom plan view of the yard light embodiment of FIG. 7; and

FIG. 12 is a right side elevational view of the yard light of FIG. 7, the left side being a mirror image.

FIG. 13 is an overall perspective view of a yard light showing a third embodiment of my design;

FIG. 14 is a front elevational view of the yard light embodiment of FIG. 13;

FIG. 15 is a rear elevational view of the yard light embodiment of FIG. 13;

FIG. 16 is a right side elevational view of the yard light embodiment of FIG. 13, the left side being a mirror image; and

FIG. 17 is a top plan view of the yard light embodiment of FIG. 13.

The bottom plan view of the yard light embodiment of FIG. 13 is the same as shown in FIG. 6.

FIG. 18 is an overall perspective view of a fourth embodiment of a yard light showing my design;

FIG. 19 is a front elevational view of the yard light embodiment of FIG. 18;

FIG. 20 is a rear elevational view of the yard light embodiment of FIG. 18;

FIG. 21 is a top plan view of the yard light embodiment of FIG. 18; and,

FIG. 22 is a right side elevational view of the yard light of FIG. 18, the left side being a mirror image.

The bottom plan view of the yard light embodiment of FIG. 18 is the same as shown in FIG. 11.

The Figures all show portions in broken lines, which are indicated for illustrative purposes only and do not form part of the claimed design.
